UNITED STATES PATENT OFFICE.

ETNA J. ALBRITTON, OF JACKSON, MISSISSIPPI.

CAR PULLER.

Application filed May 5, 1924. Serial No. 711,230.

To all whom it may concern:

Be it known that I, ETNA J. ALBRITTON, a citizen of the United States, residing at Jackson, in the county of Hinds and State 5 of Mississippi, have invented new and useful Improvements in Car Pullers, of which the following is a specification.

The object of this invention is the provision of a means whereby a vehicle, stuck 10 in mud or sand or upon an inclination, may be extricated therefrom by manually operated means in a comparatively easy and expeditious manner.

The improvement is also admirably susceptible for use in moving heavy machinery or other objects and is of such construction 15 that the same may be folded into a small compact package for storage or conveyance and quickly and easily arranged in operative position.

To the attainment of the foregoing the invention consists in the improvement as hereinafter described and definitely claimed.

In the drawings:—

Figure 1 is a view illustrating the application of the improvement.

Figure 2 is a top plan view of the improvement.

Figure 3 is a sectional view on the line 30 3—3 of Figure 2.

Figure 4 is a sectional view on the line 4—4 of Figure 3.

In Figure 1 of the drawings I have illustrated a sufficient portion of a vehicle, such 35 as an automobile, to illustrate the application of my improvement, the same being broadly indicated by the numeral 1. The vehicle is supposed to be stuck in a bog, on an incline or in sandy ground.

The improvement contemplates the employment of a yoke-like frame 2. The sides of the frame are spaced from each other by means 3 and the said sides, from the bracing and spacing means 3 are inclined inwardly toward the straight ends 4 thereof. Swivelly secured in each of the ends 4 of the frame 2 there are hooks 5 and 6 respectively. The hook 6 is connected to one end of a cable 7, the same being trained 50 through a sheave block 8 that carries a hook 9 to engage the downwardly arched end of the side bars of the frame for the vehicle 1, or any other convenient part of the vehicle at the front thereof. The cable 7 has its 55 lower strand directed toward and beneath

the frame 2, being wound around and having one end secured to a shaft or drum 10 that is journaled in bearings in the sides of the frame.

It should have been stated that the angle 60 end portions of the sides are gradually decreased in width to the ends 4 so that the lower lead of the cable will pass freely beneath the end provided with the hook 6.

The hook 5 has connected thereto a wire 65 or cable 11 which is wound around and tied on a post, tree or other upstanding rigidly supported member disposed a suitable distance from the vehicle. The post, in Figure 1 of the drawings, is indicated by the numeral 12.

The side members of the frame 2 are centrally provided with round openings to receive therethrough bearing boxes. The bearing boxes are round in plan and include 70 each a cylindrical body or barrel 13 and a head or flange 14. The barrels 13 are of a length greater than the thickness of the sides of the frame and have their outer ends threaded. Screwed on the said ends of the 75 barrels 13 there are cap members 15. Each of the cap members has an inner flanged extension 16 which is secured to the sides of the frame 2 preferably by removable means 17. The barrels of the boxes pass through 80 the openings from the inner sides of the frame and the caps 15 are provided with central openings aligning with similar openings in the boxes. There is received through each bearing box the reduced end or trunnion 18 formed on the ends of the shaft or 85 drum 10. The shaft 10 inward of one of the trunnions 18 is formed with a squared 90 reduced portion 19 that receives thereon the squared bore of a ratchet wheel 20.

In the bearing boxes there are rollers 22, the boxes in the caps forming a raceway for the said rollers so that the trunnions 18 do not contact with any part of the frame, and thus the free turning of the shaft 10 is insured.

The outer extremities of the shaft 10 beyond the trunnions 14 are reduced and are square in cross section. These portions are indicated by the numeral 23, and each of the 105 same receive thereon the square socket portion of a crank handle 24. Removable means such as cotter pins 25 pass through the squared ends 23 of the shaft for holding the crank handles thereon.

While I have described and illustrated my improvement as an extricator for automobiles, it is, of course, to be understood that the same is not to be thus restricted in its useful capacity, as the invention will be found efficient in moving any heavy objects. In instances where standing posts are not in close proximity to the object to be moved, a stake may be driven into the ground and the element 11 wound therearound. In manufacture the device will be comparatively small, although of such material that the strength thereof is insured. When not desired for use the cable 7 is wound around the drum. To prevent the strands of the cable bunching and contacting with the ratchet wheel 20 or one of the bearing boxes 13 there are passed through the said shaft or drum pins 26. The sheave block may be readily received in the frame as may be the cable 11 so that a compact package is provided for shipment or for storage when the improvement is not required for use.

I have herein illustrated and set forth a simple and satisfactory embodiment of my improvement reduced to practice, but it is to be understood that I may make such changes in the construction as fairly fall within the spirit of the invention without departing from the scope of the claim.

Having described the invention, I claim:

A device for extricating stalled vehicles, comprising a yoke-like frame, means spacing the sides of the frame, said sides, from said means being reduced to the ends of the frame, a hook swiveled in each end of the frame, and a cable attached to each hook, one of which is designed to be secured around a standing object, the other being trained through a sheave block carrying a hook to engage the stalled vehicle, the sides of the frame having round openings therethrough, bearing boxes having barrels received through the openings, caps threaded on the outer end of the barrels and secured to the sides of the frame, anti-frictional rollers in the bearing boxes, a shaft having trunnions which are journaled in the bearing boxes and having squared ends projecting from the trunnions, crank handles removably secured to the ends, a ratchet wheel on the shaft opposite one of the bearings, a pivoted pawl on the frame to engage the ratchet wheel, pins on the shaft adjacent to the ends thereof, and the lower lead of the last mentioned cable being trained around and secured to the shaft.

In testimony whereof I affix my signature.
ETNA J. ALBRITTON.
